UNITED STATES PATENT OFFICE.

ALFRED B. BELL, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

GAS-RANGE BURNER AND SUPPORT THEREFOR.

1,163,202.

Specification of Letters Patent.

Patented Dec. 7, 1915.

Application filed March 23, 1915. Serial No. 16,323.

To all whom it may concern:

Be it known that I, ALFRED B. BELL, a citizen of the United States, residing at Philadelphia, in the county of Philadelphia and State of Pennsylvania, have invented 5 certain new and useful Improvements in Gas-Range Burners and Supports Therefor, of which the following is a specification.

My invention relates to burners of improved construction for gas ranges and means for supporting the same in position in a gas range in such manner that the burners cannot by any possibility be wrongly positioned, but can only be supported in proper 10 position, and are readily applied or replaced, the arrangement being such that the burners fit closely upon the gas inlet nozzles and within the openings for the same in the front of the frame. 15 My invention is particularly intended to be applied to oven burners and is an improvement upon the construction of oven burners and support shown in the application of Caverly and Bell, Serial No. 874,961, filed December 1, 1914, but is not limited in 20 its usefulness thereto.

Specifically my invention comprises a forwardly and downwardly sloping shelf at the rear of the frame upon which rests a correspondingly inclined lower surface at the rear of the burner, the forward end of the burner being slidably mounted upon the gas inlet nozzle connected to the manifold in front of the range, the sloping supporting shelf having a forwardly extending slot therethrough, in which slidably engages a downwardly extending lug at the rear of the burner. With this construction, the burner can only be applied in proper position, as 30 otherwise it will fall off the shelf, and the provision of the forwardly sloping engaging surfaces of the rear supporting shelf and burner causes the burner to press forwardly upon the gas inlet nozzle, regardless 35 of the contraction and expansion of the parts under temperature changes, a slight longitudinal movement of the burner under working conditions being permitted by the lug and slot engagement referred to at the 40 rear of the burner.

Other features of my invention will appear in the following specification.

In order that a clearer understanding of

my invention may be had, attention is hereby directed to the accompanying drawings 55 forming part of this application and illustrating the preferred embodiment of my invention.

In the drawings Figure 1 represents a vertical longitudinal section through a burner 60 mounted in position adjacent to an oven in a gas range, the front and rear frame members being shown broken away, and Fig. 2 is a rear elevation of the burner disconnected 65 from its supports.

Referring to the drawings, the burner 1 is of cast iron construction of pipe shape, cored and drilled as usual and provided with an air mixer cover indicated at 2. The burner is slidably supported at its front 70 end on the gas inlet nozzle 3, which is connected by the usual cock 4, to the manifold 5, which latter is supported by a suitable bracket 6 from the oven front 7. The portion of the frame construction illustrated 75 at the front of the oven is similar to that illustrated in application of Caverly and Bell already referred to. In this construction, as illustrated, a heat deflector or insulation member is fastened to the oven front 80 7 in the portion thereof through which the burners extend, this comprising a sheet of metal 8 which is notched at the corners and formed into a pan with flanges 9 at the ends. It has holes pierced therein for burner cups, 85 one of which is illustrated at 10, which are made of drawn sheet-metal electric welded to member 8 along curved flanges formed on the cups and the member 8. Member 8 may be held in position by electric welding its 90 flanges 9 to the oven front 7, or by other suitable means.

The construction represented has a rear wall 11 and a rear vertical lining member, the slanting support for the rear end of the 95 burner or burners being secured to member 12. This support comprises a bent metal bar having a vertical portion 13 and a forwardly extending and downwardly slanting shelf 14, the vertical portion 13 being secured to the sheet-metal lining member 12 by means of bolts or other securing means 15, a steel angle 16 preferably being provided on the rear side of member 12 for stiffness, bolts 15 extending through members 13, 12 and 16. The sloping shelf 14 is 100 105

provided with forwardly extending slots 17, equal in number to the burners which are to be supported.

Each burner 1 is provided with a tapered lug 18 projecting downwardly from the rear end of the same and seated within slot 17 when the burner is mounted in position, slot 17 being somewhat longer than the thickness of the lug 18 engaged therein to permit lengthwise movement of the burner. The surface of burner 1 from which lug 18 projects is a plane surface, as shown at 19, extending on each side of the lug 18 and slanted with the same inclination as the shelf 14. Preferably, the rear end of the burner is formed on its upper side as indicated at 20, with a slanting projection, this insuring that the burner will not be mounted up-side-down on the shelf 14. When the burner is mounted in position as shown, the slanting flat surface 19 thereof provides a firm support on the shelf 14 so that the burner will not rock, and the inclination of surface 19 and shelf 14 tends to press the burner forwardly so that the front end wall 21 of the burner will press as far forward on the gas inlet nozzle 3 as possible, insuring a tight joint.

The enlarged portion 22 of the burner is preferably provided with an upwardly extending lug 23, which slidably engages with in a recess 24 formed in the upper portion of burner cup 10, this recess extending in the direction of the burner 1 and fitting the lug 23 fairly closely. The forward portion of the burner is also preferably provided with a downwardly extending lug 25 which engages the bottom surface of burner cup 10 when the burner is in position. These devices aid in rendering wrong application of the burner impossible. The burner may be removed by simply moving the same rearwardly and raising the rear end, the length of slot 17 and the shape of lug 23 and the burner cup 10 permitting this. When the burner is in position, it is evident that contraction and expansion of the same under

variations of temperature are permitted, while at the same time the provision of slanting surfaces 19 and 14 insure the burner 50 always being pressed forwardly into its proper position.

Having now particularly described my invention, what I claim and desire to protect by Letters Patent is as follows:

1. In a gas range, the combination of an oven having a rear vertical member, a metal shelf comprising a vertical portion secured to said member and a forwardly extending, downwardly sloping flange having a forwardly extending slot therethrough, a manifold in front of said oven having a gas nozzle directed toward said range, and a burner slidably mounted at its forward end upon said nozzle, and having a sloping lower surface at its rear end resting upon said sloping flange, and a lug extending downwardly into said slot to have sliding engagement therein, substantially as set forth.

2. In a gas range, the combination of a 70 forwardly and downwardly sloping support, a gas inlet pipe, and a burner slidably mounted on its forward end upon said pipe, and having a sloping lower surface adjacent its rear end resting upon said sloping support, the coacting surfaces of said burner and support being plane surfaces of corresponding inclination said support having a forwardly extending slot therethrough, and the sloping supporting surface of said burner 80 having a lug extending downwardly into said slot to have sliding engagement therein, said burner having a lug extending transversely therefrom, at the forward end, and a frame member having a recess in which 85 said lug is closely slidably engaged, substantially as set forth.

This specification signed and witnessed this 19th day of March, 1915.

ALFRED B. BELL.
